(57) **CLAIM**

The ornamental design for a connector, as shown and described.

DESCRIPTION

FIG. 1 is a perspective view of the connector in accordance with our design;

FIG. 2 is a top plan view of the connector;

FIG. 3 is a right side elevational view of the connector;

FIG. 4 is a left side elevational view of the connector;

FIG. 5 is a bottom plan view of the connector;

FIG. 6 is a front elevational view of the connector;

FIG. 7 is a rear elevational view of the connector;

FIG. 8 is a perspective view of a first part of the connector in accordance with our design;

FIG. 9 is a top plan view of the first part of the connector;

FIG. 10 is a right side elevational view of the first part of the connector;

FIG. 11 is a left side elevational view of the first part of the connector;

FIG. 12 is a bottom plan view of the first part of the connector;

FIG. 13 is a front elevational view of the first part of the connector;

FIG. 14 is a rear elevational view of the first part of the connector;

FIG. 15 is a perspective view of a second part of the connector in accordance with our design;

FIG. 16 is a top plan view of the second part of the connector;

FIG. 17 is a right side elevational view of the second part of the connector;

FIG. 18 is a left side elevational view of the second part of the connector;

FIG. 19 is a bottom plan view of the second part of the connector;

FIG. 20 is a front elevational view of the second part of the connector; and,

FIG. 21 is a rear elevational view of the second part of the connector.

The parts of the connector are shown separately for clarity of illustration.
